LOUNGE CHAIR WITH LEG REST

Steve J. Repaich, Los Angeles, Calif., assignor to Cali-
Quilt Furniture Corporation, Los Angeles, Calif., a
corporation of California

Application June 25, 1956, Serial No. 593,462

2 Claims. (Cl. 155—106)

This invention has to do with furniture construction and particularly with tilting lounge chairs.

An object of the invention is to provide a tilting lounge chair construction embodying a hingedly mounted leg rest with novel and improved means for actuating the leg rest as the main chair seat is tilted.

More particularly it is an object to provide a chair having a tiltable seat frame with a two-part leg rest hingedly secured at the forward end portion of the seat frame together with novel linkage means for tilting the leg rest and expanding or contracting it in response to tilting movement of the seat frame.

A further object is to provide, in a construction of the type indicated, a novel and simplified linkage means useful for the purpose above described and having other uses as well.

A further object is to provide a relatively simple actuating construction which is easily manufactured and assembled.

These and other objects will be apparent from the drawings and the following description. Referring to

Fig. 1 is a sectional view of the frame portion of a tilting lounge chair embodying the invention and shown in backward tilted position as on line 1—1 of Fig. 3;

Fig. 2 is a view similar to Fig. 1 but in upright position;

Fig. 3 is a partial plan view on line 3—3 of Fig. 1;

Fig. 4 is an enlarged fragmentary sectional view on line 4—4 of Fig. 1;

Fig. 5 is an enlarged fragmentary sectional view on line 5—5 of Fig. 2;

Fig. 6 is an enlarged fragmentary sectional view on line 6—6 of Fig. 2;

Fig. 7 is an enlarged fragmentary sectional view on line 7—7 of Fig. 1;

Fig. 8 is an enlarged fragmentary sectional view on line 8—8 of Fig. 3;

Fig. 9 is a front elevational view taken on line 9—9 of Fig. 2;

Fig. 10 is a sectional view on line 10—10 of Fig. 2; and

Fig. 11 is a fragmentary view similar to Figs. 1 and 2 but with the chair tilted to an intermediate position.

More particularly describing the invention, numeral 11 generally designates a skeleton base frame or base of a chair and this is shown as comprising a generally rectangular frame at the bottom consisting of side members 12, a rear cross member 13 and a front cross member 14. At each side is a side frame consisting of the uprights 16 and 17 and a connecting upper member 18. The frame may be made of metal and when so made the parts may be welded together, bolted or otherwise secured. It will be understood that wood upholstery frame elements (not shown) are applied to the skeleton frame shown and upholstery applied thereover.

The base frame has a transversely extending tube 21 supported upon a pair of posts 22 which are welded to

2

the frame elements 12 at each side. The tube 21 may be welded to the tops of these posts and is designed to tiltably support the seat frame, designated 25.

The seat frame includes a seat portion 26 and backrest 27. The seat portion of the seat frame comprises a pair of side rails 30, a front rail 31 and a rear crossbar 32. The backrest 27 may be formed of a pair of side rails 34 connected by cross members 28 and the two frames may be secured together by welding and by a pair of brace rods 35.

The seat frame is secured to the tube 21 of the base for tilting movement thereon by means of two laterally spaced blocks 37 which are dependently adjustably mounted on the side rails 30 of the seat portion of the seat front by means of bolts 38 extending through slots 39 in the blocks. The lower edge of each block 37 is notched at 37' to accommodate the tube 21 and an apertured plate 40 receiving the tube is attached to the block by screws 41. The above-described mounting is disclosed in my copending application for patent, Serial No. 552,528, filed December 12, 1955, entitled "Furniture Construction."

The backrest frame may be provided with a transverse strap 45 which is welded to the side members 34. Welded to strap 45 at one end 47 is a short strap 46 which is secured at its other end by bolt 48 for the purpose of mounting an electrically driven vibrator of any suitable type designated 49. It will be apparent that the vibrator mounting is such that the entire seat frame may be vibrated as desired.

The particular feature of the invention is the provision of a novel leg rest, generally indicated 50, pivotally mounted at the forward portion of the seat frame, and novel means for actuating the leg rest in response to tilting movement of the chair seat frame. The leg rest includes a rear frame 51 and a forward frame 52. The rear frame has two parallel side members 54, a center member 55 and two connecting members 56 and 57. The forward frame consists of two rails, designated 58 and 59 which are spaced by blocks 60.

The forward frame is mounted for movement toward and away from the rear frame of the leg rest and for this purpose is provided with a pair of rods 62 which are telescopically received in tubes 64 mounted in the rear frame.

The rear frame is hingedly connected to the forward portion of the seat frame to swing about an axis which is spaced somewhat above the forward edge of the seat portion of the seat frame. For this purpose the seat frame is provided with a pair of forwardly and upwardly inclined hinge straps 68 which are welded to sides 30 of the seat frame. The rear frame of the leg rest is provided with a pair of hingedly secured hinge straps 70 which are pivotally connected to the straps 68 on pins 71, respectively. The straps 70 are somewhat U-shaped between their ends and extend from the ends of straps 68 down through the seat frame and around under the front rail 31 thereof.

For the purpose of pivoting the leg rest in response to tilting movement of the chair seat frame, I provide a linkage means at each side of the chair. Each of these comprises a bell crank 80 which is pivotally mounted at 81 on mounting plate 82 depending from the side frame element 30 of the seat frame. One end of the bell crank is pivotally connected at 84 to a first link 85 which in turn is pivotally mounted upon the base at 86. The link 85 extends somewhat beyond the point of pivotal connection 84 to act as a stop and limit movement of the seat frame in a forwardly tilting direction as best shown in Fig. 2. A second link, designated 88, is pivotally connected at one end at 89 to the bell crank 80 and at its other end to the rear part of the leg rest at 90.

Preferably the pivotal points of the various levers are provided by rivets 92 (Fig. 6) in sleeves 93 which are rotatable in bores 94 in the connected elements. However, I prefer to so mount the bell cranks that there is some resistance to their pivotal movement, thereby providing a braking action upon the tilting movement of the chair. Thus, referring to Fig. 7, I show the bell crank 80 pivotally mounted on a bolt 95 and spaced from the bracket 82 by a washer 96 which is preferably formed of plastics. A nut 97 of the self-locking type together with washers 98 and a corrugated or Marcel washer 99 serve to hold the parts together and enable the placement of the required force against the parts thereby determining the stiffness of the pivotal action.

It will be apparent from the above description and the illustration of the apparatus as shown in Figs. 1, 2 and 11, that when the seat frame is in upright position the leg rest is substantially vertical as shown in Fig. 2. When the seat frame is tilted backward the leg rest is tilted upwardly through the position of Fig. 11 to that of Fig. 1.

Another feature of the invention is the means provided for expanding and contracting the parts of the leg rest. This is accomplished by providing a pair of levers 104 pivotally mounted at the points 105 upon the rear part of the leg rest frame. These levers are each pivotally connected by links 106 to the second link 88 of the linkage means and at their other ends by short links 107 to the rail 59 of the forward part of the leg rest. With the construction described, as the chair is tilted backward from the position of Fig. 2, the leg rest pivots upwardly and the forward part thereof moves outwardly to the fully extended position of Fig. 1. The leg rest returns to the position of Fig. 2 when the chair seat is moved from tilted to upright position.

Although I have illustrated and described a preferred form of my invention, I contemplate that various changes and modifications can be made therein without departing

from the invention, the scope of which is indicated by the following claims.

I claim:

1. In a tilting chair construction, a base, a seat frame mounted on the base for tilting movement about a horizontal axis, a leg rest having a rear frame hingedly secured to the forward edge of said seat frame, a pair of bell cranks pivotally mounted on opposite sides of said seat frame, a pair of normally vertical first links pivotally connected at their lower ends to opposite sides of said base and pivotally connected adjacent their upper ends to one of the ends of said bell cranks, said first links having vertical extensions at their upper ends in alignment with and adapted to act as abutments for opposite sides of said seat frame whereby to equally support and limit forward tilting movement of the seat frame, and a second pair of links pivotally connected at their inner ends to the other ends of said bell cranks and pivotally connected at their outer ends to said leg rest frame.

2. A tilting chair construction as set forth in claim 1, in which a forward frame is mounted on the rear frame of said leg rest for movement with respect thereto in a plane toward and away from said rear frame, a pair of levers pivotally mounted intermediate their ends upon the frame of said leg rest, a third pair of links connecting the inner ends of said levers to an intermediate point on said second links and means linking the other ends of said levers to the forward frame of said leg rest, said bell cranks, said links, said levers and said link means cooperating upon tilting movement of said seat frame to balance and pivot said leg rest and cause uniform relative movement between the parts thereof.
